UNITED STATES PATENT OFFICE

2,674,211

FURNACE DOOR FRAME STRUCTURE

Edward W. Pottmeyer, Pittsburgh, Pa., assignor
to Blaw-Knox Company, Pittsburgh, Pa., a cor-
poration of Delaware

Application December 23, 1949, Serial No. 134,680

8 Claims. (Cl. 110—181)

1

This invention relates to furnace structures, and particularly to an improved fastener for doorframes for furnace structures such as, for example, water-cooled doorframes for open hearth furnaces and the like.

Furnace doorframes for industrial furnaces which are exposed to high temperatures frequently deteriorate and become useless much sooner than the body of the furnace. It is therefore necessary in most industrial furnaces, to replace the doorframes during the life of the furnace. In replacing such doorframes it is economically desirable that the furnace be maintained at or near operating temperature in order to prevent the heat losses incurred in cooling and reheating and to prevent the destructive forces set up by contraction and expansion in the furnace body itself. It has been the practice in the past when a doorframe is removed to insert the new doorframe in the furnace opening, raise it into proper register with pinch bars and wedges and then bolt it at the top to the skewback channel and at the sides to the buckstays. This is a difficult and dangerous practice since the region of the furnace openings from which the frames are to be removed and replaced is at a very high temperature.

I have discovered that the difficulties, normally attendant to the changing of furnace doorframes, may be avoided by the combination which forms the subject matter of my invention. Generally my invention comprises, in combination, a furnace doorframe, supporting means pivoted on the top of said doorframe, lever means pivoted on the framing of the furnace above an opening in the furnace and gripping means on the lever means for frictionally engaging the supporting means to hold the frame in position in the furnace opening. The structure and operation of my invention will be more clearly understood, however, by referring to the accompanying drawings, in which

Figure 1 is a partial section through a furnace opening showing a conventional doorframe in position in a furnace opening;

Figure 2 is a front elevation of a furnace opening showing a conventional frame in position;

Figure 3 is a top plan view of a doorframe and fastener according to my invention;

Figure 4 is a section on the line IV—IV of Figure 3;

Figure 5 is a section similar to Figure 4 showing the fastener in the disengaged position;

Figure 6 is a top plan view of a different embodiment of my invention.

2

Figure 7 is a section on the line VII—VII of Figure 6; and

Figure 8 is a top plan view of another embodiment of my invention.

5 Figure 9 is a partial section through a furnace opening showing a doorframe incorporating the invention of this application in position in a furnace opening.

Figure 10 is a front elevation of a furnace 10 opening showing the doorframe of Figure 9 in position in the furnace opening.

Referring first to Figures 1 and 2, I have illustrated a conventional water-cooled doorframe 10 and integral skewback channel cooler 11 in place in an opening 12 in a furnace (only partially shown). The doorframe is fastened to the skewback channel 13 of the furnace by means of bolts 14 which pass through lugs 15 on the top of the doorframe and lugs 16 welded to the skewback channel. A wedge 17 is driven beneath the end of each leg 18 between the leg 18 and the breastplate 19 of the furnace so as to hold the door in position while the bolts 14 are inserted and to relieve the bolts of a part of the weight of the frame. The sides of the doorframe may be fastened to buckstays 20 of the furnace, as partially shown in chain line in

15 Figure 1, by bolts 21 which pass through wing plates 22 on either side of the doorframe. The conventional manner of installing such a doorframe is to bring the frame to the furnace and rest it upon the breastplate 19 between the foreplate 23 and the furnace body. The upper end of the frame is next moved into contact with the 20 skewback. The frame is lifted into registry with the furnace opening by means of pinch bars and wedges 17 driven beneath the legs 18 and finally, the frame is bolted to the skewback channel 13 or buckstays 20 as shown in Figures

25 30 35 40 1 and 2.

In Figures 3, 4 and 5, 9 and 10 I have illustrated a doorframe and fastening means according to one embodiment of my invention. A supporting arm 25 is fastened to a shaft 26 pivotally mounted

45 on the doorframe 10 by means of a holding member 27 welded to the frame and having an opening 28 through which the supporting arm 25 extends. A pair of lever arms 29 are fixed to a shaft 30 which is rotatably mounted in a base 31 which is in turn fixed to the skewback channel 13 above an opening in the furnace. A pair of square bars 32 are mounted for rotation between the lever arms 29. When it is desired to insert a doorframe including the combination of my invention it is 50 55 only necessary to place the doorframe before the

opening in the furnace and then insert the supporting arm 25 between the square bars 32 which are rotatably mounted between the levers 29. The doorframe is then raised into position in the opening during which time the supporting arm 25 passes between the bars 32 in contact with them. When the doorframe is released from the lifting force the square bars 32 engage the supporting arm 25 by frictional engagement and hold the doorframe in position in the furnace opening as shown in Figures 4, 9 and 10.

In Figures 6, 7 and 8 I have illustrated other and different embodiments of this invention. In Figure 6 the supporting arm 25a is engaged by the edges of a quadrangular opening 33 adjacent the end of a solid lever arm 34 which is fastened to a shaft 35 pivoted in base 36. In Figure 8 I have illustrated a supporting arm 25b of circular cross section and a circular opening 37 in a solid lever arm 38. The edges of the opening 37 engage the supporting arm 25b in the same manner as the opening 33 engages the supporting arm 25a of Figure 6. In Figure 7 I have shown an alternative method of pivoting the supporting arm 25a in which the arm is fixed to a shaft 39 which is pivoted in brackets 40 on either side of the supporting arm 25a.

While I have illustrated certain preferred embodiments of my invention as applied to water-cooled doorframes of the so-called archless type it is to be understood that it may be used with other types of furnace doorframes and may be otherwise embodied within the scope of the following claims.

I claim:

1. In combination, a furnace having a frame and a vertical furnace wall with an opening therein, a furnace doorframe fitted against said wall in registry with said opening, supporting means pivoted on the top of said doorframe for movement in a generally vertical plane substantially normal to the furnace wall, lever means pivotally attached to the furnace frame above the furnace wall opening for movement generally in substantially the vertical plane of the supporting means, and grasping means on said lever means frictionally engaging the supporting means to hold said supporting means when the angle between the said supporting means and said lever means facing said furnace wall is greater than 90° thereby to hold the doorframe in position against the vertical wall in the furnace opening.

2. In combination, a furnace having a frame and a vertical furnace wall with an opening therein, a furnace doorframe fitted against said wall in registry with said opening, at least two supporting members pivoted on the top of said doorframe for movement generally in substantially parallel vertical planes substantially normal to the furnace wall, lever arms corresponding in number and spacing to the number of supporting members pivotally attached to the frame above the furnace wall opening for movement generally in substantially the vertical plane of the supporting members, and grasping means on the lever arms frictionally engaging the corresponding supporting means to hold said supporting members when the angle between said supporting members and lever arms facing said furnace wall is greater than 90° thereby to hold the doorframe in position against the vertical wall in the furnace opening.

3. In combination, a furnace having a frame and a vertical furnace wall with an opening therein, a furnace doorframe fitted against said

wall in registry with said opening, at least two supporting members pivoted on the top of said doorframe for movement generally in substantially parallel vertical planes substantially normal to the furnace wall, lever arms corresponding in number and spacing to the number of supporting members pivotally attached to the frame above the opening in the furnace wall opening for movement generally in substantially the vertical planes of the supporting members, the free end of each of the lever arms having an aperture through which the corresponding supporting member passes vertically, said apertures permitting the supporting member to slide freely therethrough when the door frame is raised and frictionally engaging said member when the doorframe is lowered to a point where the angle between the supporting members and the corresponding lever arms facing the furnace wall exceeds 90°.

4. In combination, a furnace having a frame and a vertical furnace wall with an opening therein, a furnace doorframe fitted against said wall in registry with said opening, at least two supporting members of substantially quadrangular cross section pivoted on the top of said doorframe for movement in substantially parallel vertical planes substantially normal to the furnace wall, lever arms corresponding in number and spacing to the number of supporting members pivotally attached to the frame above the opening in the furnace wall opening for movement generally in substantially the vertical planes of the supporting members, said lever arms each having a substantially rectangular aperture in the free end thereof through which the supporting member passes vertically, said aperture permitting the supporting member to slide freely therethrough when the doorframe is raised and frictionally engaging said member when the doorframe is lowered to a point where the angle between the supporting members and the corresponding lever arms facing the furnace wall exceeds 90°.

5. In combination, a furnace having a frame and a vertical furnace wall with an opening therein, a furnace doorframe fitted against said wall in registry with said opening, at least two supporting members of substantially circular cross section pivoted on the top of said doorframe for movement in substantially parallel vertical planes substantially normal to the furnace wall, lever arms corresponding in number and spacing to the number of supporting members pivotally attached to the frame above the opening in the furnace wall opening for movement generally in substantially the vertical plane, said lever members each having a substantially circular aperture in the free end thereof through which the supporting member passes vertically, said aperture permitting the supporting member to slide freely therethrough when the doorframe is raised and frictionally engaging said member when the doorframe is lowered to a point where an angle between said supporting members and lever arms facing said furnace wall is greater than 90°.

6. In combination, a furnace having a frame and a vertical furnace wall with an opening therein, a furnace doorframe fitted against said wall in registry with said opening, at least two supporting members pivoted on the top of said doorframe for movement generally in substantially parallel vertical planes substantially normal to the furnace wall, lever arms corresponding in number and spacing to the number of sup-

porting members pivoted at one end of the frame above the opening in the furnace wall opening for movement generally in substantially the vertical plane, each of said levers having an opening in the end opposite the pivot, said opening admitting a supporting member vertically, gripping means pivoted adjacent opposite sides of said opening to lie on opposite sides of the supporting member, and said gripping means permitting the supporting member to pass freely therethrough when the doorframe is raised and frictionally engaging said member when the doorframe is lowered to a point where an angle between said supporting members and lever arms facing said furnace wall is greater than 90°.

7. A combination as claimed in claim 6 in which the gripping means are a pair of square bars pivoted so as to engage opposite sides of the supporting member.

8. A combination as claimed in claim 6 in which the lever arms comprises a pair of side members attached at one side to a shaft which is pivoted to the furnace frame and the gripping means are a pair of square bars pivoted between the ends of the side members remote from the pivot so as to engage opposite sides of the supporting member.
